Primary Examiner — Karen S Acker(74) *Attorney, Agent, or Firm* — Wilmer Cutler Pickering Hale and Dorr LLP(57) **CLAIM**

The ornamental design for a tissue, as shown and described.

DESCRIPTION

The sole FIGURE is a top plan view of a tissue according to the present design.

The broken line perimeter represents the boundaries of the claim and forms no part thereof. The segmented lines and dotted lines within the broken line boundary are part of the claimed design. The thickness of the tissue forms no part of the claim.
